UNITED STATES PATENT OFFICE.

RALPH H. MILLS, OF EAST ORANGE, NEW JERSEY, ASSIGNOR TO WESTERN ELECTRIC COMPANY, INCORPORATED, OF NEW YORK, N. Y., A CORPORATION OF NEW YORK.

SELECTIVE SIGNALING CIRCUITS.

Application filed September 29, 1924. Serial No. 740,528.

This invention relates to selective signaling circuits such as are used, for example, to associate the transmitting and receiving branches of a two-way multiplex carrier wave signaling system with a common transmission medium.

An object of the invention is to improve the transmission of such a selective signaling circuit.

Several types of carrier wave signaling systems to which the invention may be applied are described in an article by Messrs. Colpitts and Blackwell, entitled "Carrier current telephony and telegraphy" published in the Transactions of the American Institute of Electrical Engineers, Volume XL, 1921.

In the arrangements illustrated in Figs. 42 and 49 of that article the several transmitting band filters in a given system have their end sections all connected in series with each other and the common transmission circuit. Likewise, the several receiving band filters have their end sections connected in series with each other and with the common receiving circuit. The common transmitting and common receiving circuits are then connected to a common transmission line by means of a hybrid coil and balancing network.

In other known types of carrier wave signaling systems all of the band filters, both transmitting and receiving, have their end sections connected in series with each other and with the common transmission line. In other types of systems the various band filters are connected in parallel with each other and the transmission line.

In all these cases, where a plurality of band filters are connected either in parallel or in series to the common transmission line, it is customary to terminate the filters at the ends where they are joined together in a special fractional termination to improve the transmission loss characteristics of the filters in their transmitting regions at and in the vicinity of their respective cut-off frequencies. Where the filters transmit successive bands of frequencies the impedances of the respective filters when thus terminated improve the transmission characteristics at the adjacent side of the next filter on either side. The use of such fractional terminations is disclosed in a patent

of O. J. Zobel, No. 1,557,230, October 13, 1925.

Even when this type of fractional termination is employed, however, it is found that there is an uncompensated loss in the end filters of a given group at those frequencies which are not adjacent in the frequency scale to the band transmitted by another one of the filters. Such an uncompensated loss occurs, for example, at and in the vicinity of the lowest cut-off frequency of the lowest of a group of several band filters and similarly at and in the vicinity of the highest cut-off frequency of the highest of such a group of filters.

According to a feature of the invention the transmission characteristics of the lowest and highest of a group of filters operating either in parallel or in series are improved by means of simulating networks which have the same reactance as an additional adjacent filter would have at the desired cut-off frequency.

The invention will be described as applied to a multiplex carrier current telephone system, but it will be understood that it may also be applied to other signaling systems.

In the drawings:

Fig. 1 is a diagrammatic illustration of one terminal of a multiplex carrier current telephone system embodying the invention.

Fig. 2 shows curves illustrating the transmission loss characteristics of certain of the terminal filters of Fig. 1.

Fig. 3 shows curves illustrating the impedance characteristics of these filters.

Fig. 4 shows a modification of the system of Fig. 1.

The carrier terminal apparatus shown in Fig. 1 comprises a plurality of two-way carrier wave signaling channels I, II and III, each having a transmitting and a receiving branch.

The transmitting branches of these channels are connected in parallel to the transmission line ML through a common transmitting circuit TL, and the receiving branches are connected in parallel to the line ML through a common receiving circuit RL.

Transmissions in the several two-way channels I, II and III are effected by carrier waves of different frequencies. Low and high pass filters LP and HP are asso-

ciated with the common transmitting and receiving circuits TL and RL , respectively, and serve to separate the directional groups of carrier waves to the respective branches ⁵ of the several channels. These filters may be of the type disclosed in the United States patent to G. A. Campbell, No. 1,227,113, issued May 22, 1917.

The corresponding elements in the several two-way channels are much alike, differing only to the extent necessary to accommodate the different frequency carrier waves employed. For this reason only the elements of channel I will be described in detail.

Corresponding elements in the several channels are designated by the same reference letter, the channel being designated by the numeral following the letter. Certain ²⁰ of the elements of channel III have been omitted from the drawing for the sake of clearness.

The two-way carrier wave signaling channel I has in its transmitting branch a transmitting oscillator TO^1 , a modulator M^1 and a transmitting band filter TBF^1 . The receiving branch of the carrier wave signaling channel I includes a receiving band filter RBF^1 , a detector and amplifier DA^1 , a receiving oscillator RO^1 and a voice frequency filter F^1 .

A low frequency line L^1 , which may be an ordinary subscriber's telephone circuit, is conjugately connected to the transmitting and receiving branches of channel I by means of a hybrid coil H^1 and a balancing network N^1 . This conjugate connection enables independent transmission to be carried on in both directions between the line L^1 and the ³⁵ high frequency terminal apparatus. Oscillators TO^1 and RO^1 , modulator M^1 , and the detector and amplifier DA^1 may be of any suitable design, such as the well known vacuum tube type. Devices suitable for this purpose are described in the Colpitts and Blackwell article, *supra*.

The voice frequency filter F^1 may be of the ordinary low pass filter type disclosed in the Campbell patent, *supra*, and is designed ¹⁰ to transmit to the low frequency line L^1 currents of voice frequencies appearing in the output of the demodulator and amplifier DA^1 and to suppress from transmission the higher frequency components of demodulation.

The transmitting band filter TBF^1 and the receiving band filter RBF^1 may be of the composite wave filter type discussed in part ¹⁰ 3 of an article on the "Theory and design of uniform and composite electric wave-filters", by O. J. Zobel in the Bell System Technical Journal of January, 1923. These filters consist, in general, of a plurality of sections having series and shunt reactances ¹⁵ designed, according to well known laws, to

transmit with substantially negligible attenuation sinusoidal currents of all frequencies lying between two selected limiting frequencies, while attenuating and approximately extinguishing currents of neighboring frequencies lying outside of the said limiting frequencies. Filters of this type are known as suppression filters and are particularly advantageous where a sharp cut-off between frequencies in the transmitted and suppressed ranges is desired.

The carrier system outlined above is of the type in which the carrier wave of each channel is suppressed from transmission when no signals are being transmitted, and when signals are being transmitted certain of the modulation components of the modulated wave are passed to the transmission line ML , but no unmodulated components of the carrier wave are sent over the line. ⁸⁵ In order to reproduce the signal from modulated waves of this character it is necessary that the carrier wave supplied to the demodulator and amplifier DA^1 be of substantially the same frequency as the carrier wave ⁹⁰ which was suppressed at the transmitting apparatus at the distant terminal. A system of this general character is described in connection with Fig. 49 of the Colpitts and Blackwell article, *supra*.

Transmitting band filters TBF^1 , TBF^2 and TBF^3 are designed to transmit respective bands of frequencies comprised within the lower group in an ascending frequency scale. The frequencies comprised within this lower group are transmitted to the line ML through the low pass filter LP . The receiving band filters RBF^1 , RBF^2 and RBF^3 are designed to transmit respective bands of frequencies comprised within the upper group in the frequency scale which are transmitted thereto by the high pass filter HP , a certain particular band of these frequencies being diverted into filter RBF^1 , another particular band into RBF^2 and another into RBF^3 . These three bands of frequencies originated at the other or distant end of the line ML .

When the transmitting and receiving band filters of channels I, II and III are connected in parallel to the transmission line ML as shown in Fig. 1, or in series as shown in Fig. 1, or in series as shown in Fig. 4, it is well known that the transmission of each filter is affected by the impedance of the other filters which are connected to the same common transmission circuit. When the band filters are connected to the transmission line in parallel as shown in Fig. 1 they are preferably terminated at the end nearest the line ML in fractional series arms, instead of mid-series arms, in the manner disclosed in the Zobel application, hereinbefore mentioned. As described in the Zobel application, the fractional ter-

minations are so proportioned that for the free transmitting range of each filter the remaining filter or filters operate to reduce impedance irregularities of each filter.

5 A particular advantage of this arrangement is that the reactance annulling effect of each filter on either side of a given filter in the frequency displacement scale tends to improve the transmission loss characteristic of the given filter at and in the vicinity of the adjacent cut-off frequency. For example, since transmitting band filters TBF^1 , TBF^2 and TBF^3 are all connected in parallel to the common transmitting circuit TL , the transmission loss characteristic of filter TBF^2 is improved in the neighborhood of its lower cut-off frequency by the presence of filter TBF^1 and near its upper cut-off frequency by the presence of filter TBF^3 .
 10 This is shown graphically by the filter curves of Fig. 2, wherein the transmission loss of the various filters TBF^1 , TBF^2 and TBF^3 is plotted against frequency. The transmission characteristic of filter TBF^2 is improved at and in the neighborhood of its lower cut-off frequency f_2^1 by the presence of filter TBF^1 at and in the neighborhood of its upper cut-off frequency f_2^2 by the presence of filter TBF^3 . Thus, the 15 characteristic curve of filter TBF^2 indicates that there is a sharp cut-off at frequencies f_2^1 and f_2^2 between the transmitted and suppressed frequencies, and accordingly it is necessary to leave only a very small frequency margin between filter TBF^2 and the band filters adjacent thereto.
 20

The transmission characteristic of filter TBF^1 is likewise improved at its upper cut-off frequency f_1^2 by the presence of filter TBF^2 , but since no filter exists in the frequency scale below filter TBF^1 the transmission losses in the neighborhood of the lower cut-off frequency f_1^1 are practically the same as they would be if filter TBF^1 were an isolated filter, as shown by the round solid line portion of the characteristic curve of this filter at frequency f_1^1 . A similar condition exists in the neighborhood of the upper cut-off frequency f_1^2 of filter TBF^1 . Here, since no filter is present in the frequency scale above filter TBF^1 , the transmission losses of this filter in the neighborhood of its upper cut-off frequency f_1^2 are substantially the same as if filter TBF^1 were an isolated filter as also shown by the rounded solid portion of the characteristic curve of this filter.
 25

If the group of band filters were extended below the filter TBF^1 in the frequency scale, then such an added filter A adjacent the filter TBF^1 and having the dotted line transmission loss characteristic shown in Fig. 2, would have the effect of improving the transmission characteristic of the filter TBF^1 at its lower cut-off frequency f_1^1 . In

a similar manner if the group of filters were extended above filter TBF^3 in the frequency scale, then the presence of such an added filter B adjacent to the filter TBF^3 would have the effect of improving the transmission characteristic of filter TBF^3 at its upper cut-off frequency f_3^2 . This improvement is indicated by the less rounded dotted line portion of the characteristic curves at f_1^1 and at f_3^2 .
 30

In much the same way that the transmission loss of any band filter is improved near its upper cut-off frequency or near its lower cut-off frequency due to the presence of the impedance which is offered by another filter which is passing currents in the frequency scale above this upper cut-off or below this lower cut-off, applicant has discovered that the transmission loss characteristic of filter TBF^1 at its lower cut-off frequency f_1^1 may be improved in accordance with this invention by connecting in parallel therewith a simple impedance network which simulates the impedance of the fictitious filter A . In a similar manner the transmission loss characteristic of the end filter TBF^3 is improved at its upper cut-off frequency f_3^2 by means of a simple impedance network which simulates the impedance of the fictitious filter B .
 35

Fig. 3 illustrates the impedance characteristics of band filters TBF^1 , TBF^2 and TBF^3 , as well as the supposititious impedance characteristics of the fictitious band filters A and B . The impedance characteristics of the fictitious band filters A and B indicated by the dotted curves of Fig. 3 may, of course, be readily determined since these filters would be designed to transmit a well-defined range of frequencies if they were actually included in the frequency scale.
 40

The impedance of each of the filters TBF^1 , TBF^2 and TBF^3 comprises a pure resistance and a reactance. The resistance of these filters over the respective transmission ranges is indicated by the characteristic curves R^1 , R^2 and R^3 , while the respective positive reactances are indicated by curves $+x^1$, $+x^2$ and $+x^3$ and the respective negative reactances are designated by curves $-x^1$, $-x^2$ and $-x^3$. The resistance of the fictitious filters A and B over their respective transmission ranges is indicated by the dotted curves R^a and R^b . The positive and negative reactances of the fictitious filter A are indicated by the dotted curves $+x^a$ and $-x^a$, while the positive and negative reactances of filter B are indicated by the dotted characteristics $+x^b$ and $-x^b$.
 45

In order to improve the transmission loss of the band filter TBF^1 an impedance similar to that of the fictitious filter A may be inserted in parallel therewith. However, since in the present case it is only desired to improve the transmission loss of filter
 50

TBF¹ in the neighborhood of its lower cut-off frequency f_1^1 , the network which is to be inserted in parallel with the filter TBF¹ will only be required to simulate the impedance of the fictitious filter A through a small range of transmission. The impedance of the fictitious filter A at the frequency f_1^1 comprises simply the positive reactance $+x^a$, as indicated by the dotted ordinate 10 of Fig. 3. In its simplest case where filters TBF¹, TBF² and TBF³ pass bands of frequencies in an ascending scale, the reactance $+x^a$ may be only an inductance coil since an inductance coil has a positive reactance. 15 In this case, as well as when the impedance of the fictitious filter is simply a negative reactance, the value of the simulating network may be computed from the formulæ given below provided the other elements in circuit with the filter whose cut-off is to be improved are fixed impedances. This, in fact, is the general case, but where impedance irregularities exist at certain frequencies, for example, in the modulator 20 M¹ in circuit with band filter TBF¹ it is obvious that the impedance of this filter at the terminal adjacent the common transmitting circuit will differ at certain frequencies from the computed impedance represented by the impedance curve of this filter 25 in Fig. 3. When such impedance irregularities exist it is preferable to perfect the simulation network by trial, measuring the impedance of the circuit by means of any suitable measuring apparatus.

Where the elements in circuit with the filter TBF¹ are fixed impedances the value of the coil simulating the positive reactance of the fictitious filter A may be obtained 30 from the following formula: $x = 2\pi f L$, where x is the reactance that the fictitious filter A would have at frequency f and L is the resulting inductance of the coil in henries. By substituting specific values of 35 x and f in this formula it will be seen that the inductance of the coil required to approximately simulate the impedance of the fictitious filter A at the frequency f_1^1 may be represented as:

$$L = \frac{x^a}{2\pi \cdot f_1^1}$$

Therefore, by inserting in parallel with the filter TBF¹ a network such as the network SN₁, having an inductance L the transmission loss characteristic of filter TBF¹ is improved in the neighborhood of its lower cut-off frequency f_1^1 . The addition of this simulating network has the effect of sharpening the transmission loss characteristic of the filter TBF¹ in the manner indicated by the dotted portion of the characteristic curve of this filter shown in Fig. 2.

The transmission characteristic of the filter TBF³ may likewise be improved in

the neighborhood of its upper cut-off frequency f_3^2 by inserting in parallel therewith a network which simulates at this particular frequency the impedance of the fictitious filter B whose transmission band lies in the 70 frequency scale just above that of filter TBF³. At the frequency f_3^2 the impedance of the fictitious filter B is simply a negative reactance $-x^b$, as indicated by the dotted ordinate of Fig. 3. Since the reactance $-x^b$ 75 has a negative value it may be represented in its simplest case by a condenser, the capacity of which may be determined from the following formula:

$$x = \frac{1}{2\pi f c}$$

where x is the known reactance of fictitious filter B at any frequency f and c is the resulting capacity of the condenser in farads. 85 By substituting in this formula it will be seen that the capacity of the condenser required to approximately simulate the impedance of the fictitious filter B at the frequency f_3^2 may be represented as:

$$C = \frac{1}{2\pi f_3^2 x^b}$$

Therefore by inserting in parallel with the filter a network such as the network SN₂, lowering a capacity C the transmission loss characteristic of filter TBF³ is improved in the neighborhood of its upper cut-off frequency f_3^2 as indicated by the dotted portion of the characteristic curve of this filter 95 in Fig. 2. While the transmitting band filters shown in Fig. 1 have been selected for the purpose of illustrating the invention, it is to be understood that exactly the same formulæ and procedure are to be used 100 in designing simulating networks to improve the transmission characteristic of the receiving band filter RBF¹ at its lower cut-off frequency and of the receiving band filter RBF³ at its upper cut-off frequency. As 105 noted above, these filters are designed to transmit predetermined bands of frequencies in an ascending frequency scale, and accordingly the curves of Figs. 2 and 3 which have been used in connection with the description of filters TBF¹, TBF² and TBF³, also apply in every particular to the receiving band filters RBF¹, RBF² and RBF³. In this case, of course, the simulating network SN₃, designed to improve the transmission characteristic of filter RBF¹ at its lower cut-off and the simulating network SN₄, designed to improve the transmission characteristic of filter RBF³ at its upper cut-off, have values different from the networks SN₁ and SN₂, respectively, since the cut-off frequencies and impedances of the receiving band filters differ from the cut-off frequencies and impedances of the transmitting band filters. 115 120 125 130

Fig. 4 shows a modification of the invention in which the various transmitting and receiving band filters are connected in series with the transmission line instead of in parallel as has been assumed heretofore. In this case, the transmission characteristics of transmitting band filters TBF^1 and TBF^3 and of receiving band filters RBF^1 and RBF^3 may be improved by means of simulating networks connected in series in the common transmission circuit TL and the common receiving circuit RL . The two networks designed to improve the transmission characteristics of filters TBF^1 and TBF^3 are indicated schematically at TFN and the two networks designed to improve the transmission characteristics of filters RBF^1 and RBF^3 are indicated schematically at RFN . The impedance characteristics of a group of band filters connected in series is, however, somewhat different from the characteristics of the group of band filters in Fig. 1 which are connected in parallel. For example, the impedance of a fictitious filter A at the lower cut-off frequency f_1 of the filter TBF^1 of Fig. 4 instead of being a positive reactance is a negative reactance and accordingly in its simplest case the network simulating such a reactance would be a condenser instead of an inductance coil. Similarly, the impedance of a fictitious filter B at the cut-off frequency f_3 of the filter TBF^3 of Fig. 4 is a positive reactance instead of a negative reactance, and accordingly in its simplest case the network simulating this reactance would be an inductance coil. The same conditions also apply to the receiving band filters RBF^1 and RBF^3 of Fig. 4.

While the simulating networks SN_1 , SN_2 , SN_3 and SN_4 as pointed out above are designed to improve the transmission characteristics of the lowest and highest of the transmitting and receiving band filters at their respective lower and upper cut-off frequencies, it will be understood that these networks may be designed to improve the transmission characteristics of these filters at other points in the transmission range, or in fact throughout the entire transmission range of the respective filters.

Where a group of band filters such as those herein shown and described are connected either in parallel or in series to a transmission line not only does each adjacent filter have the effect of reducing the transmission loss of any filter in the neighborhood of the cut-off frequency, but they also increase the loss in the attenuating regions of the given filter where, of course, it is usually desirable to have as large a loss as possible. This beneficial effect can be produced by simulating networks which are inserted adjacent to the end filters of the group to the same degree as it would be by additional adjacent filters.

The invention may be employed to advantage in various other situations differing widely from those shown and described. For example, it may be desired to eliminate filter TBF^2 indicated graphically in Fig. 2 from the group and continue to operate filters TBF^1 and TBF^3 in the usual manner, and if filter TBF^2 were simply extracted without replacing it in any way, it is obvious that filter TBF^1 would not operate so efficiently at its upper cut-off or filter TBF^3 at its lower cut-off. Therefore, to preserve the efficient operation of filters TBF^1 and TBF^3 a simulating network may be substituted for filter TBF^2 . It would be necessary, of course, that this network simulate approximately the impedance of filter TBF^2 . A similar procedure could be followed if it were desired to eliminate either filter TBF^1 or filter TBF^3 , or both of them.

The invention has been described mainly in connection with its application to the operation of band pass filters because the use of such filters involves a transmission improvement in two regions, one just above the lower cut-off and the other just below the upper cut-off. The invention, however, is equally applicable to the operation of low and high pass filters in parallel or in series. In the case of filters of this type the improvement in the transmission range of the filters would be just below the lower cut-off and just above the upper cut-off frequencies.

Another example of the use of filter impedance simulating networks is in the operation of directional or grouping filters at repeater stations and at the terminal stations of carrier current signaling systems. Here low and high pass directional filters, such as the filters LP and HP of Fig. 1 are used in parallel, transmission occurring through one filter and reception occurring through the other, each filter being aided in its transmission near its cut-off by the presence of the other. If for some reason it is desired to remove from operation one of these parallel filters without impairing the transmission of the other, this might be done by substituting an impedance network which simulates the impedance of the filter which is withdrawn.

The invention is also susceptible of various other modifications and adaptations, and accordingly is not to be considered as limited in any way by the particular disclosure.

What is claimed is:

1. A selective system comprising a common circuit, a plurality of filters with respective mutually exclusive transmission ranges, said filters including terminal sections all of which are connected to said common circuit, and corrective means also connected to said common circuit and simulating the effect on the transmission loss

- characteristics of the filters transmitting the lowest and highest bands of frequencies which would be produced by other filters of respectively lower and higher frequency ranges.
2. A selective circuit comprising a plurality of filters with respective mutually exclusive transmission ranges, and corrective means to reduce the transmission loss of the filters transmitting the lowest and highest bands of frequencies in the neighborhood of their respective lower and upper cut-off frequencies.
3. A selective circuit comprising a transmission line, a plurality of filters for transmitting mutually exclusive bands of frequency, said filters having terminating sections connected to said line, and impedance elements also connected to said line to reduce the transmission loss over the free transmitting range of the filters transmitting the lowest and highest bands of frequencies.
4. A selective circuit comprising a plurality of filters with respective mutually exclusive transmission ranges, said filters having their terminals connected to each other and corrective means comprising reactive elements connected across said filter terminals to reduce the transmission loss in the neighborhood of the lower cut-off of the filter transmitting the lowest band of frequencies and in the neighborhood of the upper cut-off of the filter transmitting the highest band of frequencies.
5. A selective circuit comprising a transmission line, a plurality of filters with respective mutually exclusive transmission ranges connected to said line, and impedance corrective networks connected to said line to reduce the transmission loss in the neighborhood of the lower cut-off of the filter transmitting the lowest band of frequencies and in the neighborhood of the upper cut-off of the filter transmitting the highest band of frequencies.
6. A selective circuit comprising a transmission line, a plurality of filters each adapted to transmit a band of frequencies lying within the suppression range of all of the other filters, said filters being connected to said line in such a way that any given filter acts as an impedance corrective network for the adjacent filter in the neighborhood of the cut-off frequency nearest the transmission band of the given filter, and impedance elements connected to said line to reduce the transmission loss of the filters transmitting the lowest and highest frequency bands in the neighborhood of the respective lower and upper cut-off frequencies of these filters.
7. A selective circuit comprising a transmission line, a plurality of band filters joined at one end to said line so that certain frequencies may be diverted into one filter and other frequencies into another filter, and a pair of impedance networks connected to said line, one of said networks simulating the impedance of a fictitious filter adjacent the lowest filter in the frequency scale, and the other of said networks simulating the impedance of a fictitious filter adjacent the highest filter in the frequency scale.
8. A selective circuit comprising a transmission line, a plurality of band filters joined at one end to said line so that certain frequencies may be diverted into one filter and other frequencies into another filter, and a pair of impedance networks connected to said line, one of said networks simulating the impedance of a fictitious filter adjacent the lowest filter in the frequency scale at the lower cut-off thereof, and the other of said networks simulating the impedance of a fictitious filter adjacent the highest filter in the scale at the upper cut-off thereof.
9. A selective circuit comprising a transmission line, a plurality of filters with respective mutually exclusive transmission ranges connected in parallel to said line, and impedance corrective networks connected in parallel to said line to reduce the transmission loss in the neighborhood of the lower cut-off of the filter transmitting the lowest band of frequencies and in the neighborhood of the upper cut-off of the filter transmitting the highest band of frequencies.
10. A selective circuit comprising a transmission line, a plurality of band filters connected in parallel to said line so that certain frequencies may be diverted into one filter and other frequencies into another filter, and a pair of impedance networks connected in parallel to said line, one of said networks simulating the impedance of a fictitious filter adjacent the lowest filter in the frequency scale, and the other of said networks simulating the impedance of a fictitious filter adjacent the highest filter in the frequency scale.

In witness whereof, I hereunto subscribe my name this 25th day of September, A. D., 1924.

RALPH H. MILLS.
